DES
N° 1276

Design
for a Spoon Handle.
Invented July 3, 1860

Des. 1276

Henry C. Foster, of Worcester, Mass.
Letters Patent No 1276 Dated July 3. 1860,

The schedule referred to in these Letters Patent and making part of the same

To all persons to whom these presents shall come:

Be it known that I, Henry C. Foster, of Worcester, in the County of Worcester and State of Massachusetts, have invented or produced an ornamental design or configuration for the embossing or stamping of spoon handles or various other articles, and I do hereby declare the same to be fully represented in the accompanying drawing and described as follows:

The central or middle part, a, of the design consists of a plain shield provided with an ornamental boundary or border b, all of which is placed in another shield, c, whose border f, terminates at opposite ends of its longer diameter, in two leaves, d, e. That

portion of the surface of the larger shield which is between its boundary f. and the inner shield; is ornamented by a succession of waved bands, in bas. relief, the whole being as exhibited in the said drawing.

I claim the said design for the purpose set forth.
